PREFLATTEED COROX UNIT

Alfons Barnsteiner, Mansfield, Ohio, assignor to
Westinghouse Electric & Manufacturing Com-
pany, East Pittsburgh, Pa., a corporation of
Pennsylvania

Application November 30, 1937, Serial No. 177,312

2 Claims. (Cl. 219—37)

My invention relates to heating units, and more particularly, to electric range surface units adapted for relatively quick heating.

With those metal-covered surface units now known to the art in which magnesium oxide has generally been used for insulation, it has been the practice in some cases to deform or alter the cross-section of the tube or unit, such as by flattening, so that the insulating material around the heating member will be compressed, it being the object of such procedure to compact the insulating material into as dense or solid a mass as possible. In producing surface units in which there is formed a sharp angular bend within the surface sheets or plates, it has been necessary to anneal or normalize such unit so as to relieve the internal stresses set up within the sheets or plates due to such deformation. It is, therefore, an object of my invention to provide means for producing a range surface unit in which the plates may be deformed in any manner desired and in which an insulating material, such as magnesium oxide or the like will satisfactorily function without the need of normalizing or annealing the plates.

In one type of prior art surface unit it has been customary to convert magnesium metal into magnesium oxide by the use of steam or water at high temperatures and pressures, and the subsequent application of heat. These units were then deformed or flattened so as to reduce the cross-section of the space in which the magnesium oxide was contained. However, in some cases as the cross-section of such space was diminished or altered, the magnesium oxide crystals were broken and the path of heat conduction between the resistance member and the oxide walls of the retaining member was altered. It, therefore, was necessary to further flatten or deform the cross-section of such member so as to further break or pulverize the magnesium oxide crystals and to compress such pulverized magnesium oxide to form a solid, dense mass of material. It is apparent that should sufficient alteration or deformation of the container be performed to compress the magnesium oxide in such manner that the contact between the various magnesium oxide particles would be substantially equivalent to that within the original magnesium crystals, the heat conduction and dielectric strength of such mass will be substantially equivalent to that originally possible through such crystals.

It is another object of my present invention, therefore, to provide a suitably flattened or deformed container in which the magnesium oxide

crystals are retained in their original condition and still proper heat conduction and dielectric strength are obtained.

It is a further object of my invention to provide a range surface unit of high efficiency which will be capable of withstanding severe shocks and strains on the upper surface thereof and which will have an exceptionally long life. 5

A further object of my invention is to provide a range surface unit from which there will be 10 a uniform heat distribution.

A still further object of my invention is to provide means for reducing the heating element and insulation temperature while providing a desirably high cooking temperature. 15

Other objects of my invention will either be pointed out specifically in the course of the following description of a device embodying my invention, or will be apparent from such description. 20

In the accompanying sheets of drawings:

Figure 1 is a top view of a device embodying my invention;

Fig. 2 is a sectional view taken along the line II—II of Fig. 1;

Fig. 3 is an enlarged fragmentary view similar to Fig. 2;

Fig. 4 is a view taken along the line IV—IV of Fig. 1 of a preferred form of a top plate;

Fig. 5 is a bottom view of a device embodying 30 my invention in its final form;

Figs. 6 and 7 are enlarged partial sectional views taken along the lines VI—VI and VII—VII, respectively, of Fig. 5, showing the device in its preliminary form; and

Fig. 8 is a partial sectional view similar to Fig. 3, showing the surface unit in one of its stages of manufacture. 35

Like reference characters indicate like parts in the several figures. 40

Referring to the accompanying drawings, I show a range surface unit or heating unit 10 having a top plate 12, a bottom plate 14, and a resistance element 16 insulatedly mounted between the top plate and bottom plate. Each plate has two interlacing spiral grooves therein as hereinafter more fully set forth, the grooves in the top plate being in alignment with the grooves in the lower plate so that the resistance elements and spiral casings of insulation may be disposed therein. The top plate 12 has two interlacing spiral grooves 18 formed therein. These grooves have substantially flat tops and are formed in such manner that there will be sharp corners 20 between the grooves 18 and the surface plate 50 55

12. Thus the grooves 18 may be preformed in the top sheet 12 to provide the heating contact area and general shape desired in the finished surface unit. However, while forming the grooves 18 in the plate 12, considerable internal stresses and strains will be set up therein at points corresponding to the sharp corners 20 and 22. The top sheet 12 may then be normalized or annealed in such a manner that these internal stresses and 10 strains will be diminished. It is, therefore, apparent that with the internal strains removed from the top plate 12, after such top plate has been combined with the bottom plate 14 to form the surface units 10, such surface unit 10 will 15 not have to be annealed or normalized a second time.

The bottom plate 14 is preformed to produce grooves 24 having a rounded bottom. It is to be understood that the point at which the grooves 20 24 meet the main surface of the bottom sheet 14 will provide sharp corners as hereinabove described with respect to the top sheets 12. Additional flattened V-shaped grooves 28, as shown in Figs. 5 and 7, may be formed within the bottom sheet 14 so as to join adjacent whorls of the grooves 24. However, it is to be understood that the grooves 28 need not be V-shaped, although some form of groove is required in the bottom plate for the reasons hereinafter described. Likewise, ears 30 (Fig. 6) should be bent in the outer edge of the bottom sheet 14 substantially radially in line with the V-shaped grooves 28.

It is to be understood that as the grooves 24 35 and 28 and the ears 30 are formed within the bottom plate 14, substantial internal stresses and strains will be produced within the bottom sheet, and it is preferred that such sheet be annealed or normalized to relieve such stresses before being united with the top plate 12 to form the surface unit 10.

In making the range surface unit 10 using top plates 12 and 14, which have thus been preformed and normalized or annealed to relieve their internal stresses and strains, the bottom plate 14 is located substantially beneath the top plate 12 in such a manner that the grooves 24 will be in line or cooperate with the grooves 18 of the top plate. The cooperating grooves 18 and 24 will then produce 50 two hollow spaces or spiral passages 32 as shown in the sectional view of Fig. 2. The resistance element 16, preferably helical in form, and a quantity of magnesium 33, preferably in the form of a ribbon placed around or within the resistance element, or both, are located within the hollow spaces 32, after which the top plate 12 is placed upon the bottom plate 14 as shown in Fig. 8. The depending portions 34 (Fig. 4) of the top plate 12 are then bent inwardly against the bottom plate 14 so as to tightly hold it against the top plate 12 as shown at 36 in Fig. 2.

The unit comprising the top plate 12, bottom plate 14 with the resistance element 16 and the magnesium ribbon 33 located within the hollow 65 spaces 32, as above described, is placed preferably within an autoclave and subjected to steam or water at a high temperature and pressure. Such treatment converts the magnesium metal into magnesium hydroxide, which expands so as to 70 fill the hollow space 32 with a dense insulating material. The resistance element 16, due to its being located within and about the magnesium metal, will be suspended substantially in the center of the hollow spaces 32 as it becomes filled 75 with the magnesium hydroxide.

The unit 10 is then subjected to a sufficiently high temperature during a predetermined length of time to expel the moisture in the magnesium hydroxide, which in turn leaves a clear, dense compact mass of magnesium oxide crystals. The magnesium oxide crystals 38 are in intimate relationship between the resistance element 16 and the inner walls of the hollow spaces 32. In fact, it has been found from experiment that the greater percentage of these crystals will be in intimate contact with the resistance element at one end and the sides of the hollow space 32, substantially as shown in Fig. 3. The additional crystals then fill that space which is not occupied by those crystals which extend between the resistance 15 member and the side walls of the hollow space. It is, therefore, obvious that the crystals 38 will then form a heat conducting and electric insulating medium with respect to the resistance element 16. 20

As such high temperature is supplied to the heating unit either through the resistance element 16 itself, or through an additional source, the moisture within the magnesium hydroxide will be converted into steam or vapor. If no 25 means were provided for this steam or vapor to expel itself other than through the open ends of the hollow space 32, there would be the possibility of such steam or vapor increasing in pressure to such an extent that it would deform or 30 bulge the unit 10. The V-shaped grooves 28 located between the adjacent whorls of the hollow space 32 permit this steam or vapor to proceed along such grooves, located in a radial line, and to expel to the atmosphere through the depending portion or ears 30. 35

As the crystals 38 are formed within the hollow spaces 32, as hereinabove described, the resistance element 16 will be positioned relatively close to the top surface of each of the hollow spaces 40 32. This uneven positioning of the resistance element 16 will occur because of the crystals, located above the member, swelling out into the corners 39; which in turn reduce the number of crystals directly above the resistance element 16. 45 More effective coil area will, therefore, be brought close to the operating surface of the surface unit, ensuring an efficient unit which will come up to its red heat within a very short time after being connected to a supply circuit, not shown. However, the inherent compactness of the magnesium oxide crystals will provide a sufficiently high dielectric strength between the resistance element 16 and the top wall of the unit. 50

The foregoing heat and pressure treatments of 55 the unit are known to the art and constitute no part of my present invention.

Due to the inherent characteristics of the magnesium oxide crystals, the heat developed in the finished unit by the resistance element 16 60 will be uniformly distributed therefrom and, further, due to its high heat conductivity, will rapidly conduct the heat from such element to the walls of the hollow space 32. It is further obvious that due to the rapid conduction of heat 65 from the resistance element 16 to the walls of the hollow space 32, the temperature of the resistance element and of the insulation material itself will be substantially reduced with respect to former units, and, that since the resistance element is located closer to the top of the hollow space 32, more heat will be conducted upwardly and the temperature of such top plate will be greatly increased over the remainder of the hollow space 32. 70 75

After the magnesium metal has been changed to the magnesium oxide crystals in the manner hereinabove described, the plates 12 and 14 are rigidly attached together without deforming or 5 altering the cross-section of the hollow spaces 32 in any manner whatsoever. It is preferred that the two plates be spot-welded together substantially by introducing a sufficient pressure and current to the V-shaped grooves 28, where- 10 upon such grooves will be deformed into a substantially flat surface and the two plates will be welded together as shown at 40 in Fig. 2. The ears 30 will likewise be biased upwardly so as to contact the top plate 12, permitting the de- 15 pending portions 34 to be rigidly pressed against such plate, holding it against the top plate 12. If it be desired, the ears 30 may be spot welded against the top plate 12 as it is being pressed against it substantially as shown at 42 in Fig. 2.

If it be desired, a bolt 44 may be positioned 20 within a central aperture 46 in the bottom plate 14 before the unit 10 is assembled, whereupon the head 48 of the bolt 44 will hold such bolt rigidly within the aperture 46. With the bolt 44 25 rigidly attached to the unit 10 in such a manner, it is obvious that such bolt may be used to attach the surface unit to any desired supporting frame.

It will be seen that I have thus provided a 30 rugged quick-heating unit for surface cooking, which provides ample flat contact surfaces without necessitating deformation and normalizing of the metal casing after assembly.

Various modifications may be made in the de- 35 vice embodying my invention without departing from the spirit and scope thereof, and I desire, therefore, that only such limitations shall be placed thereon as are imposed by the prior art and the appended claims.

I claim as my invention:

1. The method of manufacturing a heating

unit having a top plate, a bottom plate and an insulated heating element therebetween, which method includes forming cooperating grooves in the plates, the groove in the top plate having a flattened portion whereby a relatively large contact surface is defined on the top of the plate for receiving a cooking utensil, annealing the plates to remove internal stresses and strains produced therein during the formation of the grooves, inserting a resistance element and magnesium 10 metal between the plates within the cooperating grooves subsequent to said annealing operation, then treating the assembled unit with fluid under high pressure and temperature to convert the magnesium metal into crystallized material, re- 15 moving moisture from the crystallized material and then rigidly attaching the plates together without deforming or altering the condition of the crystallized material, all of the recited steps subsequent to the annealing step providing sub- 20 stantially no annealing effect on the plates.

2. The method of manufacturing a heating unit having a top plate, a bottom plate and an insulated heating element therebetween, which method includes forming a flattened groove in 25 the top plate only, annealing said plates so as to remove internal stresses and strains therein, and, subsequent to the annealing step, inserting a resistance element and magnesium metal between the plates and within said groove, treating the 30 assembled unit with fluid under high pressure and temperature to convert the magnesium metal into magnesium oxide, treating the magnesium oxide with heat to convert it into a crystalline material, and rigidly attaching the plates together without deforming or altering the condition of the insulating material, all of the recited steps subsequent to the annealing step providing sub- 35 stantially no annealing effect on the plates.

ALFONS BARNSTEINER. 40
